[57] CLAIM

The ornamental design for an arm wrestling exercise table, as shown and described.

DESCRIPTION

FIG. 1 is a front perspective view of an arm wrestling exercise table showing my new design;

FIG. 2 is a front elevational view thereof;

FIG. 3 is a rear elevational view thereof;

FIG. 4 is a right side elevational view thereof; the side opposite being substantially a mirror image;

FIG. 5 is a top plan view thereof; and,

FIG. 6 is a bottom view thereof.
